UNITED STATES PATENT OFFICE.

OLINDO VALERI, OF ROME, ITALY.

RAILWAY-TIE.

1,362,453.

Specification of Letters Patent. Patented Dec. 14, 1920.

Application filed December 5, 1919. Serial No. 342,791.

To all whom it may concern:

Be it known that I, OLINDO VALERI, a subject of the King of Italy, and residing at 22 Lungotevere Prati, Rome, Italy, have 5 invented certain new and useful Improvements in Railway-Ties, of which the following is a specification.

This invention relates to railway ties and has for its object to provide a construction 10 which is apt to maintain the level and the gage of the track.

In the drawing—

Figure 1 shows a part of a railway track in accordance with the invention,

15 Fig. 2 is a cross section,

Fig. 3 a longitudinal section and

Fig. 4 a plan view of a block on which the rail is fastened.

1 are blocks of reinforced concrete, 2 are 20 rods intended to maintain the level and the gage of the track, 3 are rails, 4 are holes for fastening the rods 2, these holes having a larger diameter than the rods 2 so as to permit the gage being easily regulated, 4' 25 are holes for anchoring the rails on the blocks, 5 are bends of the rod 2 which end each in a hook 6 within the concrete block.

7 is a support of wood or like material interposed between the block and the rail.

The axis of the blocks does not coincide 30 with the axis of the rails, but is slightly displaced toward the outside, so that the thrust produced by the trains which tends to push over the rail and the blocks, is neutralized.

What I claim is:

35 A sub-structure for railway tracks comprising a block of reinforced concrete arranged beneath each rail with the longitudinal center of the block outwardly beyond the longitudinal center of the rail, wooden 40 supports arranged on said blocks and directly receiving the rails, and rods extending transversely of the rails, between the rails and blocks, and having down turned ends to enter enlarged openings in the blocks, the 45 rods being wholly free of contact with the rails.

In testimony whereof I have signed my name in the presence of two subscribing witnesses this 12th day of November 1919.

OLINDO VALERI.

Witnesses:

ANGELO CANATTORIO,
TORELLO FONTANE.
